UNITED STATES PATENT OFFICE

GUSTAV MEYER AND ALBERT HAACKE, OF ST. LOUIS, MISSOURI.

TRUING APPARATUS FOR CONNECTING RODS OF CRANK SHAFTS.

1,404,782.

Specification of Letters Patent. Patented Jan. 31, 1922.

Application filed May 24, 1920. Serial No. 383,725.

To all whom it may concern:

Be it known that we, GUSTAV MEYER and ALBERT HAACKE, citizens of the United States, residing at St. Louis, State of Missouri, have invented certain new and useful Improvements in Truing Apparatus for Connecting Rods of Crank Shafts, of which the following is a full, clear, and exact description, reference being had to the accompanying drawings, forming a part hereof.

The present invention is directed to improvements in truing apparatus for the connecting rods of crank-shafts, the object sought being to provide suitable means for supporting the crank-shaft during the truing of the connecting rod and the piston coupled thereto relatively to the axis of the shaft, the apparatus being provided with means for supporting a square adapted to be applied directly to the periphery of the piston and thereby measure the extent to which the axis of the piston and connecting rod departs from a line which is perpendicular to the axis of the shaft. The advantages of the apparatus will be apparent from the following detailed description in connection with the accompanying drawings in which—

Figure 1 represents a side elevation of the invention showing the manner of applying the same; Fig. 2 is a vertical cross-section on the line 2—2 of Fig. 1; Fig. 3 is a top plan of the device; Fig. 4 is a diagonal cross-section through the face plate on the line 4—4 of Fig. 2; Fig. 5 is a perspective of the front end of the gage-bar showing the square resting on the same; and Fig. 6 is a diagrammatic elevation of the face plate showing the application thereto of flanges of different diameters.

Referring to the drawings, 1 represents a work bench or table to which is bolted the base 2 of a suitable standard 3 the front end of the base terminating in a circular face plate 4 which connects to the standard at the top, the top of the standard and face plate being provided with a longitudinally disposed groove *a* in which is free to slide a gage bar 5, one of the bounding walls *w* of the groove on the standard being provided with a perforated boss *b* for the reception of the stem 6 of a clamping screw, the stem terminating at the top in an enlarged head 6' under which the bar 5 slides, so that by turning the screw in proper di-

rection the head 6' may forcibly engage the bar and clamp the same in any position to which the bar may have been moved. The bar 5 is provided on one side at one end thereof with a guard 7 against which bears 60 the short leg of a conventional combination square *S* when deposited on the bar for gaging the angle through which the axis of the piston has been deflected from the perpendicular to the axis of the crank shaft 65 with any bending or straining of the connecting rod, as will hereinafter more fully appear.

The face plate 4 is provided near the bottom of the front face thereon with two pins or studs 8, 8, spaced apart and disposed normally in a horizontal plane, said pins serving as initial supports for the flange 9 forming one of the terminals of the crank-shaft 10, the outer face of the 70 flange as well understood in the art being perpendicular to the axis of the shaft, so that if the face of the flange is brought into engagement with the front face of the plate 4, the axis of the shaft will be perpendicular 75 to the plane of said face. In this connection it may be stated that the bottom of the groove *a* in which slides the bar 5 is parallel to the axis of the face plate or perpendicular to the front face of the face plate, 80 so that when the crank-shaft is properly mounted, the path of movement of the bar 5 will be parallel to the axis of the crank-shaft. Secured to the face plate between the pins 8, 8, is a stud-bolt 11 over which is 85 passed a bent L-shaped washer or jaw 12 the larger leg operating freely between the pins and the short leg limiting the inward movement of the jaw by coming in contact with the face plate 4. A nut 13 on the outside of the jaw clamps the jaw to or loosens it from the flange 9 as presently will more fully appear. The face plate 4 is provided with two (or more if desired) radial slots 90 *s*, one on either side of a vertical diameter 100 through the stud bolt 11, the slots being formed with lateral offsets or recesses *r* along the inner wall of the face plate for receiving the heads 14 of suitable machine bolts 15 traversing the slots *s*, the bolts 105 having loosely passed over the outer projecting portions thereof the jaws 12' similar in construction to the jaw 12, and being clamped to or loosened from the flange 9 by nuts 13'. By providing elongated slots 110

such as s , it is apparent that the jaws 12' may be adjusted radially to accommodate flanges of different diameters, no radial adjustment being necessary for the jaw

- 5 12. The connecting rod 16 connecting the crank-shaft to the piston 17 often becomes bent or sprung out of true perpendicular to the axis of the shaft; and in order to properly square it up to said axis, 10 it is desirable that the shaft be rigidly supported with its axis preferably in a horizontal plane so that the amount of deflection of the axis of the piston and of the connecting rod from a true perpendicular to 15 the shaft axis may be accurately gaged. This deflection being ascertained by the application of the square S to the piston periphery, the connecting rod may then be readily squared to the crank-shaft as will 20 be apparent from the following description of the operation of the invention:

Let us assume that the connecting rod 16 has been sprung or bent from a true perpendicular to the axis of the crank-shaft.

- 25 The machinist thereupon removes the crank-shaft from the crank-case of the engine, depositing the edge or periphery of the flange 9 thereon upon the pins 8, 8, bringing the edge of the flange behind the jaw 12 which is loosened sufficiently for the purpose, the bolts 15 and jaws 12' being moved outward so as to permit the flange 9 to be brought 30 squarely against the face plate 4, after which the bolts 15 are moved inward to bring the 35 jaws 12' over the flange, and the nuts 13, 13', screwed down so as to clamp the flange tightly to the plate and thus support the crank-shaft, the plate 4 being set in a vertical plane so as to have the axis of the shaft 40 perfectly horizontal. The connecting rod 16 with its piston 17 is swung into a vertical position or across the path of movement of the gage-bar 5 (where they will remain), after which, by loosening the screw-head 6' 45 from the gage bar 5, the latter is pushed forward in its guide or groove a until the end carrying the guard 7 is brought close to the piston, after which the square S is deposited on the bar against the guard as shown in 50 Figs. 1 and 5, thus bringing the outer edge of the vertical leg of the square in contact with the periphery of the piston. If the contact is not uniform and shows a deflection of the piston from a true vertical, the 55 machinist takes a wrench or equivalent tool and applies it to the connecting rod, bending the latter in proper direction until an even contact is effected between the leg of the square and piston periphery. This being accomplished, the machinist knows that the connecting rod and its piston are squared up to the crank-shaft. The crank-shaft is then removed from the plate 4 and restored to its engine. It may be stated in passing 60 that the crank-shaft is so forged that the 65

outer face of the flange 9 is at right angles to the shaft axis, so that when the piston shows an even contact with the outer edge of the square S deposited on the gage bar 5, the machinist knows that the deflection in 70 the rod has been corrected. In the present example, only one end of the crank-shaft is shown supported. In case of any danger of the crank-shaft sagging from a true horizontal (as for example in the case of a very 75 long shaft) the other end may be allowed to rest on a suitable adjustable prop or post (not shown) so as to relieve the plate 4 of a portion of its load. Such a provision would of course fall within the purview of 80 the skilled mechanic. The construction here shown may obviously be departed from in many particulars without in any wise affecting the nature or spirit of the invention. It is obvious of course that the face plate 4 85 will accommodate flanges of different diameters, and in Fig. 6 is shown diagrammatically the face plate 4 with a series of dotted circles 9, 9', 9'', 9''', illustrating different diameters of flanges, the pins 8, 8, being so 90 positioned as to support any flange that may be deposited thereon, and the slots s being sufficient to permit the bolts 15 traversing the same to be shifted to proper position to cause the jaws 12' thereof to engage any 95 flange applied to the plate 4. The apparatus need not of course be limited in its application to the truing of crank-shafts.

Having described our invention what we claim is:

1. In an apparatus of the character described, a fixed support, means for securing thereto one end of a crank-shaft, a gage-bar mounted slidably on the support and movable parallel to the axis of the shaft 105 thus supported, the bar being adapted to receive a square applied to the periphery of the piston coupled to the connecting rod leading from the crank-shaft.

2. In an apparatus of the character described, a fixed support, means for securing thereto one end of a crank-shaft carrying a piston and connecting rod, a gage-bar mounted slidably on the support and movable longitudinally parallel to the axis of the shaft thus supported, the bar being adapted to receive a square applied to the periphery of the piston swung across the path of movement of the bar, and a guard on the side of the bar for engaging the 115 square deposited thereon.

3. In an apparatus of the character described, a fixed support, a face plate thereon, means on the face plate for securing thereto the terminal flange of a crank-shaft, 125 and maintaining the shaft supported with its axis at right angles to the face plate, a gage-bar mounted slidably on the support and capable of longitudinal movement across the face plate in a path parallel to 130

the axis of the shaft, the bar being adapted to support at one end thereof a square adapted to be applied to the periphery of a piston coupled to the crank-shaft.

5 4. In an apparatus of the character described, a fixed support, a face plate thereon, a pair of pins projecting from the lower portion of the plate and spaced apart, a jaw mounted on the face plate between the 10 pins, the plate being provided with elongated radial slots on either side of a diameter passing between the pins aforesaid, sliding jaws mounted in said slots, the several jaws operating to grip and hold the 15 terminal flange of a crank-shaft deposited with its edge on the pins aforesaid and bearing against the face plate, a top groove or way being formed in the support and face plate and disposed parallel to the axis of 20 the shaft thus supported, and a square-supporting gage bar mounted slidably in said groove to present the square deposited thereon against the periphery of a piston coupled to the crank-shaft.

25 5. In an apparatus of the character described, a face plate, a stud bolt projecting therefrom, a jaw mounted loosely on the bolt, pins projecting from the face plate parallel to and on either side of the bolt, 30 radial elongated slots being formed in the face plate on either side of a vertical diameter through the stud-bolt, the plate being provided with offsets or recesses on its inner face leading from the slots, machine 35 bolts traversing said slots and projecting through the front of the face-plate, the inner ends of the bolts terminating in heads traversing said recesses, jaws on the outer projecting ends of the bolts, the several jaws 40 operating to grip and hold the terminal flange of a crank-shaft deposited with its outer face against the plate and with its edge resting on the pins aforesaid, nuts on the bolts for driving the jaws to the flange, 45 and a gage-bar mounted slidably on the support and movable longitudinally across the face plate in a path parallel to the axis of the crank-shaft thus supported, the bar being adapted to support a square applied to 50 the periphery of a piston leading from the crank-shaft and swung across the path of

movement of the gage-bar and square supported thereby.

6. In an apparatus of the character described, a suitable standard, a face plate 55 secured thereto, a groove formed in the top of the standard and face plate and disposed transverse to the faces of the plate, a gage-bar slidably mounted in said groove, and means on the face plate for securing thereto 60 one end of a crank-shaft maintained with its axis parallel to the path of movement of the gage-bar.

7. In an apparatus of the character described, a fixed support, means for securing 65 thereto a crank-shaft in a position to project outwardly from said support, a gage-bar mounted slidably on the support and movable longitudinally parallel to the axis of the shaft thus supported, the bar being 70 adapted to receive a square applied with one leg thereof to the periphery of the piston coupled to the crank-shaft and swung across the path of movement of the bar and square deposited thereon. 75

8. In a device of the character described, a portable standard provided with a base and a face plate secured thereto, the latter being provided with means for co-operating with the face plate for securing thereto the 80 terminal flange of a crank-shaft, and the base being provided with means for securing the standard to a suitable support.

9. In a device of the character described, a portable standard provided with a base 85 and a face plate secured thereto, the latter being provided with radially adjustable means for securing thereto the terminal flange of a crank-shaft, and the base being provided with means for securing the stand- 90 ard to a suitable support.

10. In a device of the character described, a portable standard provided with a base and a face plate secured thereto, clamping means projecting from the face plate and 95 adjustable for securing to the face plate the terminal flange of a crank-shaft.

In testimony whereof we affix our signatures at St. Louis, State of Missouri, this 21st day of May, 1920.

GUSTAV MEYER.
ALBERT HAACKE.
